UNITED STATES PATENT OFFICE

2,159,696

ELECTRIC VENTILATOR

Walter R. Gross, Grosse Pointe, Mich.

Application June 1, 1937, Serial No. 145,874

1 Claim. (Cl. 98—88)

This invention relates to a ventilator adapted to be placed in windows and the like, the general object of the invention being to provide an adjustable frame adapted to be placed in windows of varying widths and provided with pivoted shutters operated by an electric motor which is controlled from a distant point, whereby one lying in bed, for instance, can open and close the shutters by simply manipulating a switch placed close at hand and which controls the circuit to the motor.

This invention also consists in certain other features of construction and in the combination and arrangement of several parts, to be herein-after fully described, illustrated in the accompanying drawings and specifically pointed out in the appended claim.

In describing the invention in detail, reference will be had to the accompanying drawings where- 20 in like characters denote like or corresponding parts throughout the several views, and in which:

Figure 1 is a front view of the ventilator.

Figure 2 is a rear view thereof.

Figure 3 is a section on the line 3—3 of Figure 2.

Figure 4 is a section on the line 4—4 of Figure 2.

Figure 5 is a section on the line 5—5 of Figure 2.

Figure 6 is a longitudinal sectional view through the device.

Figure 7 is a perspective view of one of the shutters.

In these drawings, the numeral 1 indicates a rectangular-shaped frame, preferably formed of angle iron and having channel-shaped bars 2 fitting over its ends. As shown more particularly in Figure 2 each bar has a pin 3 adjacent each end thereof which extends through the channel 40 and through holes in the end member of the frame and through a hole in a bracket 4 fastened to the inner face of the side member of the frame. A spring 5 encircles each pin and bears against a part of the bracket and against the channel bar and these springs act to press the bar outwardly. Each pin 3 has its inner end upset as at 3' in Figure 6 to prevent the bars 2 from being entirely removed off the ends of the frame. Thus the bars 2 will engage parts of a window frame to hold the main frame 1 therein with the main frame passing across an opening formed by partly opening one sash. By pressing inwardly one of the bars 2, by the handles 6 thereon the length of the device is shortened so that it can be removed from the window opening

and placed therein. While the drawings show the handles 6 carried by but one of the bars 2 it will be understood that if desired similar handles can be connected to the other bar 2.

A plurality of shutters 7 extend longitudinally in the frame 1 and have pintles 8 at their ends which pass through holes in the end members of the frame 1, the shutters overlapping when closed, as shown in Figure 4 with the upper and lower shutters engaging parts of the frame 1 as also shown in Figure 4.

Right angular projections 9 are formed on the shutters at one end thereof and these projections are connected together by a bar 10 so that the shutters will move in unison and a curved strap 11 is connected with the inner face of the lower-most shutter and passes through a hole 12 formed in a motor housing 13 where the other end of the strap is connected to a pitman 14 which is eccentrically pivoted to a worm wheel 15 engaged by a worm 16 of a motor M arranged in the housing, the housing being connected to a part of the frame 1.

The motor is adapted to be connected to any suitable source of electric supply by the conductors 17 and the current is controlled by a switch 18 connected with the conductor 19 so that the switch can be placed at a remote point from the device, such, for instance, adjacent the bed of a person so that such person can open and shut the shutters without leaving the bed. When the motor is in operation it rotates the worm wheel 15 and this wheel through the connections shown will open and close the shutters so that it is simply necessary to stop the motor 35 when the shutters are in the desired position.

From the foregoing it will be seen that I have provided a ventilator of simple construction and one which can fit various sizes of windows, and the shutters of which are operated by a motor 40 so that it is simply necessary to close the circuit to the motor to open and close the shutters and by locating the switch of the motor circuit at a distant point one can open and close the shutters without leaving his seat or bed and with practically no effort.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:

A ventilator of the class described comprising an elongated frame, a plurality of shutters having pintles at their ends journaled in the ends of the frame, one end of each shutter being cut adjacent one side edge thereof and the portion between the cut and said side edge being bent at right angles, a bar pivotally connected to said bent portions for causing the shutters to move in unison, a motor housing supported at one end

of the frame, a worm wheel rotatably supported in the housing, a pitman eccentrically connected with the wheel, a bent strap pivoted to the pitman and connected with one of the shutters, the motor housing having an opening therein through which the strap passes, a motor in the housing, a worm on the motor shaft engaging the worm wheel and a remote switch controlling the circuit of the motor.

WALTER R. GROSS. 10
